(57) **CLAIM**

The ornamental design for a flat switch module, as shown and described.

DESCRIPTION

FIG. 1 is a front view showing the OFF status of a flat switch module of the first embodiment.

FIG. 2 is a right side view of the flat switch module in FIG. 1.

FIG. 3 is a left side view of the flat switch module in FIG. 1.

FIG. 4 is a top view of the flat switch module in FIG. 1.

FIG. 5 is a bottom view of the flat switch module in FIG. 1.

FIG. 6 is a perspective view of the flat switch module in FIG. 1.

FIG. 7 is a front view showing the ON status of the flat switch module of the first embodiment.

FIG. 8 is a right side view of the flat switch module in FIG. 7.

FIG. 9 is a left side view of the flat switch module in FIG. 7.

FIG. 10 is a top view of the flat switch module in FIG. 7.

FIG. 11 is a bottom view of the flat switch module in FIG. 7.

FIG. 12 is a perspective view of the flat switch module in FIG. 7.

FIG. 13 is a front view showing the OFF status of a flat switch module of the second embodiment.

FIG. 14 is a right side view of the flat switch module in FIG. 13.

FIG. 15 is a left side view of the flat switch module in FIG. 13.

FIG. 16 is a top view of the flat switch module in FIG. 13.

FIG. 17 is a bottom view of the flat switch module in FIG. 13.

FIG. 18 is a perspective view of the flat switch module in FIG. 13.

FIG. 19 is a front view showing the ON status of the flat switch module of the second embodiment.

FIG. 20 is a right side view of the flat switch module in FIG. 19.

FIG. 21 is a left side view of the flat switch module in FIG. 19.

FIG. 22 is a top view of the flat switch module in FIG. 19.

FIG. 23 is a bottom view of the flat switch module in FIG. 19.

(Continued)

FIG. 24 is a perspective view of the flat switch module in FIG. 19.

FIG. 25 is a front view showing the OFF status of a flat switch module of the third embodiment.

FIG. 26 is a right side view of the flat switch module in FIG. 25.

FIG. 27 is a left side view of the flat switch module in FIG. 25.

FIG. 28 is a top view of the flat switch module in FIG. 25.

FIG. 29 is a bottom view of the flat switch module in FIG. 25.

FIG. 30 is a perspective view of the flat switch module in FIG. 25.

FIG. 31 is a front view showing the ON status of the flat switch module of the third embodiment.

FIG. 32 is a right side view of the flat switch module in FIG. 31.

FIG. 33 is a left side view of the flat switch module in FIG. 31.

FIG. 34 is a top view of the flat switch module in FIG. 31.

FIG. 35 is a bottom view of the flat switch module in FIG. 31; and,

FIG. 36 is a perspective view of the flat switch module in FIG. 31.

The broken line showing of the flat switch module is for illustrative purpose only and forms no part of the claimed design.
